UNITED STATES PATENT OFFICE

ELMER O. BEARDSLEY AND WALTER F. PIPER, OF CHICAGO, ILLINOIS, ASSIGNORS TO THE BEARDSLEY & PIPER COMPANY, OF CHICAGO, ILLINOIS, A CORPORATION OF ILLINOIS

PORTABLE MOLDING MACHINE

Application filed February 15, 1926. Serial No. 88,181.

The invention relates to portable molding machines.

One object of the present invention is to improve portable molding machines of the type exemplified in our Patent No. 1,408,796 dated March 7, 1922, by equipping the wheeled truck, on which the projector is carried, with means for conveniently placing flasks into and out of the range of the projector to avoid delays or time losses in flask-filling.

Another object is to provide an improved construction in this type of machine, for housing the motor and driving mechanism.

Other objects will appear from the following detailed description.

The invention consists in the several novel features hereinafter set forth and more particularly defined by claims at the conclusion hereof.

In the drawings: Fig. 1 is a side elevation. Fig. 1a is a detail section of the pivotal bearing for the crane-arm. Fig. 2 is a rear elevation. Fig. 3 is a front elevation. Fig. 3b is a section on line 3b—3b of Fig. 3. Fig. 3c is a section on line 3c—3c of Fig. 3. Fig. 4 is a section on line 4—4 of Fig. 1. Fig. 4a is a section on line 4a—4a of Fig. 1. Fig. 4b is a side elevation, showing the pawl and ratchet mechanism for propelling the truck. Fig. 5 is a section on line 5—5 of Fig. 1. Fig. 5a is a section on line 5a—5a of Fig. 5.

The invention is exemplified with a wheeled truck-frame adapted to travel on tracks in the molding room floor. This frame comprises sides 10 and 11, which are rigidly cross-connected by pipes 12 and 13. Pipe 13 is secured by U-bolts 16 to the frame-sides. Pipe 12 is secured to the frame-sides by U-bolts 18. The rear of the truck is sustained by a pair of traction-wheels 21 having toothed peripheries 22 meshing with rack 23 on rails 24 set into the molding room floor. A shaft 26 extends through pipe 13 and connects wheels 21 for conjoint rotation. The front of the truck is supported by wheels 27 which ride on flat portions of rails 24. A supporting-base for the machine for projecting sand

into flasks comprises a cast-frame 35 which is secured, by U-bolts 37, to pipe 13, and by U-bolts 41 to pipe 12. A cast-standard 60, for supporting the upper end of a sand elevator, is secured on frame 35 by U-bolts 41.

The molding machine on the truck comprises a jib 44 pivoted to swing horizontally on a post 42 carried by frame 35; an arm 45, which is pivoted at 44a on the outer end of jib 44, so it may swing horizontally relatively to said jib; a sand-projector 46 on the outer end of arm 45; an electric motor 47, mounted on said arm and connected to drive the rotor of the projector; a vibratory chute 48 mounted to swing with jib 44, and into which sand is delivered by the elevator; mechanism for vibrating the chute mounted to swing with jib 44 and contained in a housing 49; and an endless feed belt, which is mounted to swing with arm 45, receives sand from chute 48 and delivers it to the projector, and is driven by the motor 47. This structure may be of the construction set forth in our Patent No. 1,408,493 dated March 7, 1922, to which reference may be had for a more detailed description, and exemplifies a sand-projector which is mounted on a truck and is supported so it may be moved horizontally over subjacent flasks to fill all portions thereof.

To supply a stream of sand to the projector from a pile on the floor ahead of the truck, a cross-conveyor, consisting of spiral blades 54, 55 fixed to a shaft 58 which is suitably journalled in the frame-sides 11 and 12, conveys sand from the pile laterally to a centrally disposed elevator which discharges the sand into chute 48. This elevator comprises an endless chain 56 and buckets 61 on the chain. The chain is driven by a sprocket 57 on shaft 58 and passes around an idler sprocket 59, suitably mounted at the upper end of standard 60. The mechanism for driving the cross-conveyor and elevator comprises an electric-motor 68; a pinion 71 on the motor shaft; a gear-wheel 72, meshing with pinion 71 and mounted on frame-side 11; a pinion 74 rigid with gear 72; and a gear 75 which meshes

with pinion 74 and is fixed to one end of the cross-conveyor shaft 58. This structure exemplifies mechanism on the truck for conveying sand from a pile on the floor to the 5 molding-machine on the truck.

The mechanism for driving the traction wheels, to propel the truck into the pile of sand on the floor, comprises an eccentric pin 76, rotating with shaft 58; a pawl 78 pivoted to and reciprocated by said pin, and a ratchet-wheel 79 operated by said pawl; and a pinion 80 rigid with said ratchet-wheel and meshing with one of the traction-wheels 21.

15 The motor 68 and the gearing driven thereby are enclosed to exclude sand therefrom. In the present invention, the side frame 11 is formed with a bottom wall 11^a, an end-wall 11^b and side-walls 11^c which 20 form a chamber 68^a for motor 68 and with an integral transversely extending wall 11^d, which forms a chamber 11^e for gears 71, 72, 74 and 75. The outer side of this chamber 11^e is formed by a removable plate 11^f 25 which is removably secured to the side frame by bolts 11^g, so that access to the gears may be provided when desired. A removable plate 11^r is provided on the front side-wall 11^c to provide access to the motor. The top 30 of the chamber 68^a is formed by a plate-like casting 11^h which is removably secured by bolts 11^k to close the top of the chamber 68^a. To provide for the circulation of air around the motor 68 to keep it cool, inlet 35 ducts 11^l and 11ⁿ are formed in the top plate, and an outlet duct 11^m is also formed in said plate. Electric motors are usually equipped with means for circulating air through the casing so that air will be drawn 40 into ducts 11^l, 11ⁿ and discharged through duct 11^m while the motor is running. The motor 68 is secured by bolts 68^b to the plate 11^h, so that it will be removable with said plate for convenient inspection or access 45 when a motor repair is necessary. This construction exemplifies means for housing the electric motor and the gearing driven thereby, which is composed of walls integrally formed with one of the frame sides, 50 and in which provision for the circulation of air is made around the motor. The air ducts open laterally, so that there is little likelihood of sand being drawn into them.

55 In the operation of molding machines of the tractor type, it is desirable to bring flasks within the range of the projector with sufficient speed so that there will be no idle period, and one object of the invention is to equip the truck with means for this purpose. The cross pipe 12 of the truck frame is extended to project laterally from either side to support masts 80. These masts are formed of pipes, and the lower end of each is fixed in a fitting 81 which is seated on 60 frame pipe 12 and fixedly secured thereon

by U-bolts 82. The upper portions of the masts 80 are secured laterally by pipes 83. The outer end of each pipe is provided with a fitting 84 which is seated against the mast and fixedly secured thereon by U-bolts 85. 70 The inner end of each pipe 83 is secured by a U-bolt 86 to a lug 87 which is bolted to one side of the elevator supporting mast 60 (Fig. 3b). The masts are additionally secured by inclined tubular braces 88, the upper ends of which extend to lugs 89 on fittings 84, and the lower ends of which extend to lugs 90 on plates 91 which are fixed to the front of the frame-sides 11 and 12 respectively. Rods 92 extend through pipes 88 and the lugs at the ends thereof, to fixedly secure said pipes to the frame structure. The upper end of each mast 80 pivotally supports a crane-arm 94. Said arm comprises an I-beam 95 and a bracket 96, to which the beam is fixedly secured, and which is provided with a socket 97 around the upper end of one of the masts 80. The socket is supported around the mast by a lower ball-bearing 98 and an upper ball-bearing 99. 80 A cap 100 is secured to, and closes the upper end of, the mast 80, being secured thereto by screws 101 which are threaded to a plug 102 which is fastened in the mast by a pin 103. Cap 100 extends over packing 104 in the socket 99 to exclude sand from the upper bearing. A plate 105 fits in an opening in the top of the socket to cover the cap. Packing 106 is suitably held in the lower end of socket 97, to prevent sand from 85 working into the lower ball-bearing. 90

95 The crane-arm 94 is adapted to support a hoist of any suitable construction, as exemplified by a pneumatic cylinder 107 containing a piston for raising and lowering a rod 108 which carries at its lower end a hook 109 adapted to engage the usual blade on a flask, so that it can be raised and lowered by the lift. The cylinder 107 is suspended from a carriage 110 provided with rollers 111 adapted to run on the lower flange of the I-beam 95, so that the flask may be transported lengthwise of the arm and to and from the mast. 100

105 In operation, the truck-frame is propelled forwardly slowly towards the pile of sand from which the projector will be supplied while the operator moves the projector laterally to fill all portions of a flask at the rear of the truck. While one flask is being filled, another flask from a row at either side of the path of travel of the truck may be connected to the hoist, elevated and brought into position to be deposited on the floor within range of the projector, by swinging the crane-arm and, if necessary, shifting the hoist with the suspended flask longitudinally of the arm. While one crane arm is being used to remove a filled flask, the other may be used to bring another flask 110

within range of the projector, so that the latter may be kept supplied with empty flasks to avoid idle periods.

The invention exemplifies a portable molding machine of the tractor type, which is equipped with lifting mechanism for bringing the flasks into and out of the range of the projector; which is simple in construction, and which forms a part of the truck by which the projector is supported and which makes it possible to avoid time losses, so that the projector may be worked to its maximum capacity.

The invention is not to be understood as restricted to the details set forth, since these may be modified within the scope of the appended claims, without departing from the spirit and scope of the invention.

Having thus described the invention, what we claim as new and desire to secure by Letters Patent, is:

1. The combination of a truck adapted to travel along a row of flasks on a foundry floor, said truck comprising side frames and a cross-member, a mast secured to the outer end of said cross-member, an arm pivotally mounted on the mast and operative to swing the flasks into and out of position adjacent the truck, a molding machine for filling the flasks mounted on the truck, and means for delivering sand to the molding machine.

2. The combination of a truck adapted to travel along a row of flasks on a foundry floor, said truck comprising side frames and a cross-member extended to project beyond the said frames, a mast secured to the outer end of said cross-member, a crane-arm and operative to move the flasks from the rows into and out of position adjacent the truck mounted on the mast, a hoist movably mounted on the arm, a molding machine for filling the flasks mounted on the truck, and means for delivering sand to the molding machine.

3. The combination of a truck adapted to travel over a foundry floor between rows of flasks, said truck comprising side frames and a cross-member extended to project laterally beyond said frames, masts supported at the outer ends of said cross-member, crane-arms mounted on the masts respectively and operative to swing the flasks from the rows into and out of position adjacent the truck, a molding machine for filling the flasks, mounted on the truck, and means for delivering sand to the molding machine.

4. The combination of a truck adapted to travel over a foundry floor between rows of flasks, said truck comprising side frames and a cross-member extended to project laterally beyond said frames, tubular masts clamped to the outer ends of said cross-member, crane-arms mounted on the masts respectively and operative to swing the flask from the rows into and out of posi-

tion adjacent the truck, a molding machine for filling the flasks mounted on the truck, propelling mechanism on the truck, and means for delivering sand to the molding machine.

5. The combination with a truck adapted to travel along a row of flasks on a foundry floor, a molding machine mounted on the truck, mechanism for propelling the truck, mechanism for conveying sand to the molding machine, the truck comprising side frames and a cross-member, a mast secured to one end of said cross-member, a crane-arm pivotally mounted on the mast, a hoist movably mounted on the arm and adapted to be used in moving the flasks from the row into and out of a position to be filled by said molding machine, and brace-members between the mast and the truck-frame.

6. The combination with a truck adapted to travel over a foundry floor between rows of flasks, a molding machine mounted on the truck, mechanism for propelling the truck, mechanism mounted on the truck for conveying sand to the molding machine, the truck comprising side frames and a cross-member, masts secured to the outer ends of said cross-member, crane arms pivotally mounted on the masts, hoists movably mounted on the arms respectively and adapted for use in moving the flasks from the row into and out of position to be filled by said molding machine, and brace-members between the masts and the frame-sides.

7. The combination with a truck adapted to travel along a row of flasks, on a foundry floor, a molding machine mounted on the truck, mechanism on the truck for propelling it, mechanism for conveying sand to the molding machine comprising an elevator, an elevator standard on the truck, the truck comprising side frames and a cross-member, a mast secured to the outer end of said cross-member, a crane arm pivotally mounted on the mast, a hoist movably mounted on the arm and adapted for use in moving the flasks from the row into and out of a position to be filled by said molding machine, and a brace-member between the mast and the standard.

8. The combination with a truck adapted to travel along a row of flasks, on a foundry floor, a molding machine mounted on the truck, mechanism on the truck for propelling it, mechanism for conveying sand to the molding machine comprising an elevator, an elevator standard on the truck, the truck comprising side frames and a cross-member, a mast secured to the outer end of said cross-member, a crane-arm pivotally mounted on the mast, a hoist movably mounted on the arm adapted for use in moving the flasks from the row into and out of a position to be filled by the molding ma-

chine, and brace-members between the mast and the standard and a side-frame.

9. The combination with a truck and adapted to travel over a foundry floor between rows of flasks, a molding machine mounted on the truck, mechanism for propelling the truck, mechanism mounted on the truck for conveying sand to the molding machine, a central standard on the truck, the truck comprising side-frames and a cross-member, masts secured to the outer ends of said cross-member, crane-arms pivotally mounted on the masts, hoists movably mounted on the arms respectively and adapted for use in moving the flasks from the rows into and out of position to be filled by the molding machine, and brace-members between the masts and the standard and the side-frames.

20. Signed at Chicago, Illinois, this 2nd day of February, 1926.

ELMER O. BEARDSLEY.
WALTER F. PIPER.
